United States Patent Office

Des. 227,482

Patented June 26, 1973

227,482

TELEPHONE INSTRUMENT

Ronald Binks, Chambersburg, Pa., assignor to Global
Systems Design Corporation, Chambersburg, Pa.

Filed May 30, 1972, Ser. No. 258,212

Term of patent 14 years

Int. Cl. D14—03

U.S. Cl. D26—14 A

FIG. 3

FIG. 4

FIG. 5

FIG. 6

FIG. 7

FIG. 1 is a perspective view of a telephone instrument showing my new design;

FIG. 2 is a perspective view thereof, with the handset separated from the telephone instrument base;

FIG. 3 is a top plan view thereof on a reduced scale;

FIG. 4 is a side elevation thereof on a reduced scale;

FIG. 5 is a side elevation thereof on a reduced scale as seen from the opposite direction of FIG. 4;

FIG. 6 is a front elevation thereof on a reduced scale; and

FIG. 7 is a rear elevation thereof on a reduced scale.

I claim:

The ornamental design for a telephone instrument, substantially as shown and described.
